UNITED STATES PATENT OFFICE.

CHARLES LEDIN, OF STAMFORD, CONNECTICUT, ASSIGNOR TO THE YALE & TOWNE MANUFACTURING COMPANY, OF STAMFORD, CONNECTICUT.

CYLINDER LOCK.

Application filed February 24, 1926. Serial No. 90,336.

This invention relates to improvements in cylinder locks, one object of the invention being to provide simple and efficient means including the utilization of the plug cam, 5 normally to positively lock the plug or turning member against rotary movement.

A further object is to so construct a cylinder lock that the cam carried by the plug shall normally have interlocking relation 10 with the stationary shell or casing and be releasable from such relation by longitudinal movement of the plug upon the insertion of and lengthwise pressure on the key.

With these and other objects in view, the 15 invention consists in certain novel features of construction and combinations of parts as hereinafter set forth and pointed out in the claims.

In the accompanying drawings:

20 Figure 1 is a view in side elevation of a cylinder lock embodying my improvements;

Figure 2 is a front end view;

Figure 3 is a rear end view;

25 Figure 4 is a longitudinal sectional view with the plug shown in elevation;

Figure 5 is a longitudinal sectional view of the shell or casing;

Figure 6 is a front end view of the shell or casing;

30 Figure 7 is a rear end view of said shell or casing;

Figure 8 is a view in side elevation showing the plug;

Figure 9 is a front end view of the plug;

35 Figure 10 is a rear end view of the plug, and

Figure 11 is a view of the spring.

In the drawings, my improvements are 40 shown as applied to a cylinder lock of the sliding tumbler type, but it will be understood that said improvements are applicable as well to a pin-tumbler lock, or any other type of cylinder lock.

45 The lock shell or casing is represented at 1, and it may be provided with grooves 2, 2 to receive sliding tumblers 3 carried by the plug or barrel member 4 of the lock.

The plug 4 is provided at its rear end 50 with an eccentrically located stud 5, which provides a bearing for a roller cam 6. This roller is normally seated in one or another of open slots or recesses 7 formed in the rear end of the shell or casing 1 and when so seated, the plug will be positively locked

against rotation, by cooperation of said 55 roller with the shoulders 7^a, 7^b formed by the end walls of said slots or recesses. The plug 4 is longitudinally movable and retained in its normal position with the roller cam in one of the slots, by the action of a 60 spring 8. This spring may have a general annular shape and made of spring sheet metal, said spring being so formed that portions 8^a thereof will be disposed in a different plane from that of the outer edge 65 thereof. The shell or casing 1 is recessed in its front end portion to provide one or more shoulders 9 against which the peripheral portion of the spring 8 is seated, the raised 70 portions 8^a of said spring bearing against the rear face of the head 4^a of the plug. It will be apparent the spring 8 will operate normally to retain the plug in the position shown in Figure 4 and when in this position, the roller cam will be seated in one of the 75 slots or recesses 7 at the rear end of the shell or casing.

If it be desired that the plug shall be given a half rotation in one direction only to unlock, the rear end of the shell of casing 80 1 may be so formed that the shoulders 7^b will be greater in depth than the shoulders 7^a.

When a key is inserted into the plug of the lock and pressed, the plug will be moved longitudinally so as to release the roller cam 85 from locked relation to the shell or casing. The movement of the plug will be sufficient to move the roller cam beyond the shoulder 7^a but not far enough to move said roller beyond the shoulder 7^b. The plug may now 90 be given a half turn as the roller cam will clear the shoulder 7^a at one end of each of the slots or recesses 7, but its further turning movement will be arrested by engagement of the roller cam with the shoulder 7^b 95 at one end of the slot or recess 7 diametrically opposite the slot or recess in which said roller was normally disposed. Thus it will be seen that the plug may be given a half turn in one direction to effect unlocking, and then turned backwardly to normal 100 position, instead of making a complete rotation of the plug in the same direction.

Having fully described my invention what I claim as new and desire to secure by Letters Patent is:—

1. In a cylinder lock, the combination of a shell or casing, a longitudinally movable

and rotatable spring-pressed plug, said shell or casing having a slot, and a cam carried by the plug and normally entering said slot.

2. In a cylinder lock, the combination of a shell or casing having an open slot at one end, a longitudinally movable and rotatable plug, a roller cam carried by said plug and normally entering said slot in the shell or casing, and a spring normally holding the plug in position to insure engagement of said cam roller in said slot.

3. In a cylinder lock, the combination of a shell or casing having at one end diametrically opposite pairs of spaced shoulders, one shoulder of each pair being of greater depth than the other, a longitudinally movable and rotatable plug, a cam carried by said plug, a spring pressing said plug outwardly to

maintain said cam between the shoulders of one pair and permitting the plug to be moved longitudinally to cause said cam to clear one shoulder only of each pair.

4. In a cylinder lock, the combination of a shell or casing having at one end spaced shoulders and a diametrically opposite stop shoulder, a longitudinally movable and rotatable plug, a cam carried by said plug and adapted to enter between said spaced shoulders and when given a half turn to engage said stop shoulder, and a spring cooperable with the plug and the shell or casing to normally retain said cam between said spaced shoulders.

In testimony whereof, I have signed this specification.

CHARLES LEDIN.
